UNITED STATES PATENT OFFICE.

FRANK F. BEEBY, OF CHICAGO, ILLINOIS, ASSIGNOR TO CEMENT-GUN CONSTRUCTION COMPANY, OF CHICAGO, ILLINOIS, A CORPORATION OF ILLINOIS.

PROTECTED PILE AND PROCESS OF MAKING IT.

Application filed March 24, 1922. Serial No. 546,348.

To all whom it may concern:

Be it known that I, FRANK F. BEEBY, a citizen of the United States, residing at Chicago, in the county of Cook and State of Illinois, have invented a certain new and useful Improvement in Protected Piles and Processes of Making Them, of which the following is a specification.

My invention relates to a composite wood 10 and concrete pile, or rather to a sheathed wood pile, and to the process of producing it. It has for particular purpose to provide a pile which shall resist the teredo, and therefore comprises a pile which is sheathed in a 15 resistance coating, preferably concrete, from a point above the high water mark to a point preferably beneath the bottom into which the pile is to be driven. It will be understood that these piles are for use in 20 salt water, where the teredo lives, wood piles in the teredo zone being very rapidly attacked by that animal and shortly reduced to a mere honeycomb, which finally breaks and crumbles. The object of my invention is to 25 provide a teredo-resistant pile in which the resistant coating shall be impervious to action of the teredo, shall be easily applied to the pile, shall be firmly and permanently secured when applied, and shall be so mounted 30 on and secured to the pile as not to be disturbed by the operation of driving the pile into place. Other objects will appear from time to time in the course of the specification.

35 I illustrate my invention more or less in the accompanying drawings, wherein—

Figure 1 is a view of a pile with a concrete coating in place;

Figure 2 is a view with parts broken 40 away and parts in section, showing the lower portion of the concrete sheathing together with the reinforcing structure;

Figure 3 is a section on the line 3—3 of Fig. 2;

45 Figure 4 is a view of the process of preparing the pile, and

Figure 5 is a section through the structure shown in Fig. 4.

Like parts are indicated by like characters throughout the specification and drawings.

50 A is any suitable pile body, preferably having a sharpened or tapered point A¹. The pile is prepared for the concrete coating 55 by the cutting in it of a peripheral notch

B, which fixes the lowest point of the sheath. The notch preferably comprises a lower surface B¹ lying in a plane perpendicular to the axis of the pile and an upper inclined surface B², as shown in Fig. 2. C is any 60 suitable reinforcing structure, preferably a welded wire mesh of any suitable dimensions, although of course other reinforcing structures may be used.

The wire mesh comes in sheets and is 65 preferably rolled from the sheet about the pile, the mesh being secured to the pile and spaced therefrom by spacing elements D, the details of which do not form part of the present invention but which are provided 70 with spacing slots D¹ to engage the wire mesh, both mesh and spacing clip being secured in position by the nails D², which are driven directly through the clip and into the pile and which close the spacing slots 75 D¹. The ends of the wire mesh sheath may be overlapped as at E. The lower end of the reinforcing is crimped down into the notch, as shown in Fig. 2, and this crimping may be accomplished by kinking the 80 lower horizontal wire F of the wire mesh sheet, which in turn bends in the lower ends of the vertical strands F¹.

To the reinforcing structure thus prepared concrete or any other suitable protecting material is applied by any suitable means. Preferably a rather liquid cement is projected against the pile from a cement gun until the reinforcing structure is entirely coated, and the finished pile is provided with a concrete coating or sheath, which fills the notch at its bottom and inclines or curves outwardly therefrom to reach the full diameter of the sheathing. The concrete sheath G thus is provided with 95 a tapered lower portion G¹, the bottom of which is entirely shielded by the notch B, in such wise that the material or bottom into which the pile is driven cannot strip the sheath off the pile or start breakage or 100 crumbling at the bottom of the sheath.

The pile may be prepared in a number of ways and the coating may be cast if desired, but I prefer to mount the pile vertically in any suitable rack H, as shown in 105 Fig. 4, which may be provided with any suitable upper holding member H¹ and lower holding member H², in which the pile may be revolved either mechanically in any suitable manner or by the use of cant hooks. 110

5 Adjacent the vertical pile are a series of horizontal galleries H³, spaced about 7 feet apart or any other suitable distance, in order to permit operators to project cement 5 against the pile as it is rotated.

The reinforcing structure may be similarly applied, prior to the cement projection, or, if more convenient, it may be applied to the pile when the pile is in horizontal 10 position, the pile being rolled upon the mesh sheet or the mesh sheet secured to and drawn over the pile as it is rotated, workmen, of course, spacing it from the pile by the spacing and holding clips, as 15 the sheet is bent about and applied to the pile.

Obviously, the pile itself is susceptible of many variations of detail, and the process of manufacture might be almost infinitely 20 varied without departing from the spirit of my invention. I therefore do not wish to be limited to the details of the specification and drawings, which I regard as largely 25 representative.

25 I claim:

1. The process of preparing a composite pile which consists in peripherally notching the pile, rolling about the pile body an integral sheet of reinforcing material and 30 securing said sheet to it and spacing it from the pile progressively as the sheet is rolled thereabout, crimping the bottom of the reinforcing sheet into the notch, and finally covering the entire reinforcing structure 35 and filling the notch with concrete.

2. A composite pile comprising a pile body having a peripheral notch thereabout, a reinforced concrete sheath about said pile above said notch, the lower edge of said 40 sheath being received in said notch and being protected by the lower wall thereof.

3. A composite pile comprising a pile body having a peripheral notch thereabout and a protecting sheath about the pile above said notch, said sheath in contact with the 45 normal surface of the pile throughout substantially the entire length of the sheath, the lower edge of said sheath being received in said notch and protected by the lower wall thereof. 50

4. A composite pile comprising a pile body having a peripheral notch thereabout, a reinforcing structure mounted about said pile above said notch, the lower edge of said reinforcing structure penetrating said 55 notch, and a coating of concrete surrounding said pile above said notch, embedding said reinforcing structure and filling said notch, the lower edge of said concrete coating being tapered down to meet the edge of 60 the lower wall of said notch.

5. The process of preparing a protected pile which consists in peripherally notching the pile body at one point, placing a reinforcing structure about said pile body above 65 said notch, projecting concrete against said pile to embed said reinforcing structure and to fill said notch and tapering the lower edge of the concrete coating thus formed.

6. The process of preparing a composite 70 pile, which consists in peripherally notching the pile, surrounding the pile above the notch with a reinforcing network, carrying the lower portion of said network into the notch, and projecting concrete against the 75 pile to embed and cover said network and fill said notch.

Signed at Chicago, county of Cook and State of Illinois, this 22nd day of March 1922.

FRANK F. BEEBY.
